(57) **CLAIM**

The ornamental design for a holder for soldering iron, as shown and described.

DESCRIPTION

FIG. 1 is a first perspective view of a holder for soldering iron;

FIG. 2 is a second perspective view thereof;

FIG. 3 is a front view thereof;

FIG. 4 is a left side view thereof;

FIG. 5 is a right side view thereof;

FIG. 6 is a top view thereof;

FIG. 7 is a 7-7 sectional view thereof;

FIG. 8 is a 8-8 sectional view thereof; and,

FIG. 9 is a 9-9 sectional view thereof.

The broken lines depict portions of the holder for soldering iron in which the design is embodied that are not considered part of the claimed design.
